(57) **CLAIM**

The ornamental design for a planetary mixer, as shown and described.

DESCRIPTION

FIG. 1 is a top perspective view of a planetary mixer showing my new ornamental design;

FIG. 2 is a top plan view thereof;

FIG. 3 is a right side view of FIG. 2 thereof;

FIG. 4 is a left side view thereof;

FIG. 5 is a rear view thereof;

FIG. 6 is a front view thereof; and,

FIG. 7 is a bottom plan view thereof.

The broken line showing in FIGS. 1-7 is included for the purpose of illustrating environmental structure and forms no part of the claimed design.
